UNITED STATES PATENT OFFICE.

GEORGE H. GIDDINGS, OF ILION, NEW YORK.

SINGLE-TRIGGER DEVICE.

1,302,910.

Specification of Letters Patent.

Patented May 6, 1919.

Application filed October 4, 1918. Serial No. 256,836.

To all whom it may concern:

Be it known that I, GEORGE H. GIDDINGS, a citizen of the United States, residing at Ilion, in the county of Herkimer and the State of New York, have invented certain new and useful Improvements in Single-Trigger Devices, of which the following is a specification.

This invention relates to means whereby one trigger only is employed for a double barrel gun, of either the over and under or side by side type. I have illustrated the invention as applied to a gun of the type first mentioned.

In a gun of this over and under type the one trigger discharges the barrels alternately, commencing with either the upper or the lower barrel, or one barrel may be discharged successively, the other one remaining unused.

The invention also consists in the novel features of construction hereinafter described, pointed out in the claims and shown in the accompanying drawings, in which:—

Figure 1 is a longitudinal, vertical sectional view showing parts in position to discharge the upper barrel first.

Figs. 2, 3, and 4 are plan views of the trigger plate and parts carried thereby, movable parts being in different positions, and a tang screw block being in section.

Fig. 5 is a side elevation of a trigger blade.

Fig. 6 is a detail plan view of the blade.

Fig. 7 is a detail view of a trigger blade post and selective button.

Fig. 8 is a side elevation of an escapement.

Fig. 9 is a detail view of an escapement post.

Fig. 10 is a view of one of the hammers.

Fig. 11 is a broken detail section corresponding to Fig. 1.

In these drawings 1 designates the gun frame, 1^a a main tang screw block, slotted, 2 a trigger plate, and 3 a slot in said trigger plate.

Two hammers 4 are each provided with cam portions 5 and two sears 6 are employed.

All of these parts are shown and described in detail in my application now on file and bearing Serial No. 251,259.

A trigger blade post 7 has its shank working in the slot 3, and carries on its lower end portion a selective button 8. The upper inner end of the post is slotted to receive a trigger blade 9. This blade has at its forward end a vertically arranged loop 10 and its rear end is forked as at 11.

The blade post 7 is rotatable in the slot 3 as well as slid able and the trigger blade is mounted in the post for vertical swinging movement. This allows for two blade movements, one vertical and one lateral. The vertical movement is due to a spring 12 and the lateral to a spring 13.

The lateral movement of the blade is under the control of an escapement 16 and escapement posts 14 and 15.

In the loop portion 10 is mounted a roller 17 adapted for engagement with the cam portions 5 of the hammers.

The trigger blade is in operative engagement with the usual trigger 9^a.

It will be seen in Fig. 1 that the trigger plate 2 is in section showing a side view of trigger mechanism and that blade post 7 extends through the slot 3 and is held on the outside by the selective button 8 which is screwed into the post shank.

When selective button 8 is set in its forward position as seen in Fig. 1 the roller 17 will coöperate with the cam 5 of the right hand hammer 4, which fires upper barrel, and when hammers are thrown into cocked position by opening of the gun, as described in the application above referred to, it will carry the rear end of blade 9 in its lateral movement to the right, that is under the right hand sear 6, controlling the upper barrel. The rear end of blade 9 then rests below a lateral extension on the rear end of the sear and above the trigger, or between the trigger and the sear. If therefore the trigger is pulled the blade is forced upward carrying the rear end of the sear with it. This fires the upper barrel. The sear remains in this lifted position allowing blade

to ride from under it and over to the left side of the gun, actuated vertically by spring 12 and laterally by spring 13.

This causes the blade to take a position 5 under the left hand sear 6, as shown in dotted lines in Fig. 2.

By shifting the selective button to the rear of the slot 3 the action of the parts is reversed, and the lower barrel is fired first.

10 It will be noted that if the operator fires but one barrel and then opens the gun and reloads the trigger mechanism will operate for that one barrel only, returning to the same position each time the gun is reloaded.

15 In double barrel guns controlled by one trigger there is a movement caused by the recoil to be overcome. This is termed the involuntary pull, that is the finger strikes the trigger the second time involuntarily, 20 producing a double discharge when not desired.

To prevent this I fork the rear end of the blade 9 as shown at 11 and provide the escapement 16 and the posts 14 and 15.

25 In Fig. 2 it will be noted that the blade is under the right hand sear 6 and the button 8 is in forward position, as in Fig. 1. In this case both members of the fork 11 are to the right of the center escapement block

30 16 and in position to actuate the right hand sear. When the trigger and sear are pulled the fork 11 rides upward along the right hand side of the escapement center block and on release of the trigger, the blade actuated by spring 12, rocks on its pivot and the forked end rides down again until it can pass under the block 16, which is angled as shown in Fig. 8, then actuated by spring 13, the blade passes under the block and

40 strikes the cone shaped escapement post 15, causing blade to rise again. This post is struck by the left hand member of the fork and as the blade rises to clear the post the right hand member of the fork strikes the 45 right hand side of the block. This position is shown in Fig. 4 and may be termed the neutral position of the blade 9. This position is held for only an instant but long enough to prevent blade passing under the 50 left hand sear until the effect of the recoil is over. Consequently contact of the finger with the trigger while the blade is in neutral position will not fire the gun.

The same action, in reverse, takes place 55 when the selective button is in its rear position.

Spring 13 actuates blade in both right and left hand directions, as the shifting of the button 8 changes the bearing which the free 60 end of the spring 13 takes on the blade post 7.

From the drawings and the description given above it is thought that the device will

be readily understood by those accustomed to the manufacture and use of firearms. 65

This invention while adapted to use with guns having side by side barrels, is also to be considered in connection with the application above mentioned.

What I claim is:—

1. In a double barrel gun having two hammers, provided each with a cam portion and two sears, of a movable trigger blade post, a blade mounted therein to swing vertically and laterally, springs for producing said blade movements, and a trigger for actuating said blade, the blade swinging alternately under lateral spring pressure from one sear to the other, and a roller carried by the blade. 70

2. In a one trigger device for double barrel guns, a vertically and laterally movable trigger blade, a slideable blade post, a spring for lifting the blade vertically and a spring for swinging the blade laterally, 85 a roller carried by the forward end of the blade and adapted to engage the hammers, and a fork at the rear end of the blade, an escapement center block, and escapement posts on opposite sides of said block, said 90 block and posts being engaged by the forked end of the blade.

3. In a device of the kind described, a slotted trigger plate, a blade post having its shank working loosely in said slot, a selective button on the outer end of the shank, a blade mounted to rock vertically in the post, and a spring having its free end bearing on the blade post, said spring bearing on opposite sides of the post center as the 100 shank is shifted from end to end of said slot. 95

4. The combination with a vertical and laterally swinging trigger blade, an angled escapement block adapted to be engaged by the 105 rear forked portion of the blade, conical escapement posts arranged on opposite sides of the escapement block and adapted to retard lateral movement of the blade, and means for actuating said blade. 110

5. In a double barrel gun having duplicate hammers and sears, of a trigger blade adapted to alternately engage said hammers and sears as long as the gun remains unopened, and a retarding means comprising a 115 forked end portion carried by the blade, an angled escapement block, and conical posts arranged on opposite sides of the block, said fork member passing under the block, and one member of the fork engaging the block as the other member strikes and rides up one of said posts, thereby retarding momentarily lateral movement of the blade from one sear to the other. 120

6. In a device of the kind described, a 125 slotted trigger plate, a blade post rotatable

and slideable in the slot, a blade having a rear forked end, a roller carried by the forward end of the blade, a spring for imparting vertical rocking movement to the blade, 5 a spring bearing on the post block and giving lateral movement to the blade, the bearing point of said spring shifting when the post is moved from one end of the slot to the other, a trigger adapted to engage the 10 blade, hammers adapted to engage said

roller on cocking of the hammer and give lateral movement to the blade, and an escapement adapted to engage said forked end of the blade and regulate lateral movement of the blade as and for the purpose 15 set forth.

In testimony whereof I have affixed my signature.

GEORGE H. GIDDINGS.
